202,634

GAME BOARD

Alfred R. Hetherwick, Hanover, Mich., assignor to John Fern Products, Union City, Mich.

Filed Mar. 1, 1965, Ser. No. 84,028

Term of patent 14 years

(Cl. D34—5)

FIG. 1

FIG. 2

The figure is a perspective view of a "game panel," showing my new design.

The dominant feature of my design resides in the portions shown in full lines.

I claim:

The ornamental design for a game panel, as shown and described.

References Cited by the Examiner

UNITED STATES PATENTS

D. 122,901	10/40	Marvin	-----	D34—5
D. 168,217	11/52	Durant	-----	D34—5
3,023,004	2/62	Pitts.

EDWIN H. HUNTER, Primary Examiner.